UNITED STATES PATENT OFFICE.

VITTORIO EMILIO WIECHMANN, OF FLORENCE, ITALY.

ATOMIZER.

Application filed March 23, 1923, Serial No. 627,092, and in Italy March 29, 1922.

The present invention relates to a vaporizer or atomizer intended more particularly for producing medicated vapors for inhaling in the treatment of patients.

5 One of the principal objects of the present invention is to provide an atomizer which will produce a nebula of very fine dry vapor from liquids of all classes, particularly those of an oleaginous nature, and which at the
10 same time can be used for the ejection of a coarse spray.

Another object is to provide an atomizer which may be constructed almost entirely of glass so as to permit ready inspection and cleansing of the interior thereof.

A further object is to provide an atomizer which may be freely carried about when filled with liquid without danger of spilling the contents.

20 The apparatus consists in the container, for the liquid to be vaporized, and is provided with a small blow-pipe to which is attached an aspirator immersed in the liquid, the liquid emerging from the mouth of
25 which is converted into spray by the continuous jet of air proceeding from the blow-pipe. Both these organs open into a bell, chamber, or the like, within which is formed the nebula (or dry and cold vapour), which
30 nebula, by means of the pressure arising within the apparatus, is expelled therefrom, passing underneath the edges of the bell, and after circulating through the empty space between the bell and the external vessel,
35 emerges from an appropriate duct. The liquid, converted into spray, but not yet into an actual nebula, but into small particles or drops, is dashed against the inner walls of said bell; and, condensing, drips
40 back into the container; thus, while only the nebula of the medicated or other liquid escapes regularly, every drop of the liquid is intercepted and recovered.

This fact is obviously due to the location of the bell in the interior of the apparatus and the positioning of the upper portions of the air and liquid tubes within said bell.

The accompanying drawing shows a practical example of the invention. Therein:

50 Fig. 1 indicates the apparatus, as a whole, comprising the bulb, in a front view;

Fig. 2 in vertical section;

Fig. 3 in a side view.

The apparatus is composed of a container —*a*— (preferably of glass) supported at its lower portion by a base —*b*— and pro-

vided with a mouth —*c*— for insertion in the duct connected to a bulb —*d*—.

Said mouth —*c*— is in communication with a small tube or pipe —*e*— ending at its upper part in a comparatively small aperture. Said tube or pipe acts as a blow-pipe and carries, attached thereto, another small pipe —*f*— extending into the liquid to be atomized, and whose upper end slightly surmounts the mouth of the blow-pipe. 65

In the upper portion of the container —*a*—, is located the organ intended to intercept the drops, namely, the bell —*g*— which covers, to a certain extent, the ends 70 of the two tubes or pipes —*e*—, —*f*—.

The upper part of the bell *g* communicates with the mouth *h* for the purpose of introducing liquid into the container or for the ejection of a coarse vapor therefrom, a stopper being provided for closing the mouth when the atomizer is used for fine spray. 75

A lateral duct —*i*— serves for the expulsion of the atomized liquid.

The liquid to be atomized having been introduced into the container in such a quantity that the small tube or pipe —*f*— is freely immersed therein, air is admitted, by means of the common bulb —*d*—, into the duct —*c*—. The air, passing through the small tube or pipe —*e*— and escaping from its upper vent, brings about suction in the small tube or pipe —*f*—, which draws in the liquid in which it is immersed and causes it to issue from its upper mouth, upon which —as already stated—it becomes atomized. 85 90

The nebula thus produced in the interior of the bell —*g*— passing beneath the latter —as stated—is thence expelled from the 95 small tube or pipe —*i*— through the pressure of the air, and the drops eventually formed as a result of the liquid escaping from the upper mouth of —*f*— are dashed against the walls of said bell, being thus intercepted and 100 falling back into the container.

Thus the nebula is left devoid of any drop which, where medicated liquid, or the like, is concerned, might injure or irritate the mucous membranes or cavities which the nebula is intended to heal. 105

Claim:

An atomizer for vaporizing liquid comprising a container for said liquid having an elongated opening in its top, a bell shaped member vertically suspended within the container having its lower end positioned above 110

the normal liquid level in said container and having in its top an opening forming a continuation of said elongated opening, a stopper for closing said elongated opening, 5 atomizing means communicating with said liquid for discharging atomized liquid into said member, a laterally disposed discharge tube communicating with the container at the upper portion thereof and adapted, when 10 said elongated opening is closed, to discharge

the vapor escaping thru the bottom of said member, said elongated opening forming the inlet for admitting liquid into the container and an outlet for the ejection of a coarse vapor therefrom when said stopper is 15 removed.

In testimony whereof I have signed my name to this specification.

VITTORIO EMILIO WIECHMANN.
